TELEPHONE SYSTEM

Eduard Wochinger, Berlin, Germany, assignor to
 Siemens & Halske Aktiengesellschaft, Werner-
 werk, Siemensstadt, near Berlin, Germany

Application April 14, 1938, Serial No. 202,099
 In Germany April 17, 1937

24 Claims. (Cl. 179—27)

The invention relates to telephone systems in which subscribers belonging to different groups are able to reach the same connecting lines. The groups of subscribers may differ in that for example the calling arrangements are different (i. e., with or without call registering) or the feeding current arrangements for the subscriber may differ (local or central battery feeding), or the mode of working (fully or semi-automatic) may be different or the groups may belong to different exchanges.

If for example the difference resides in that the one group contains subscribers with call registering while the other contains subscribers without call registering it may happen that when the traffic is heavy among the subscribers with call registering the connecting lines which become free from time to time are immediately seized by other subscribers using call registering, as a result of this latter feature, while the subscribers without call registering always find the connecting lines busy so long as there are any registered calls present, unless they reach the connecting line just during the short period between the release of the connecting line after a previous call and the new seizure by a registered call. The same difficulty may be experienced by the operator serving to extend subscribers calls when she wishes to deal with calls for example in the opposite direction. In order to avoid such difficulties the arrangement according to the invention is such that switching means in the connecting lines place these exclusively at the disposal of a calling subscriber of the one group only after having been influenced by a switching operation on the part of an operator serving the subscribers or after the expiry of a definite period from the time of release of the connecting line after a previous call so that if desired a call outgoing from a subscriber of the other group can be dealt with over the connecting lines before a call outgoing from a subscriber of the first group.

Embodiments of the invention are represented in the Figures 1-7, Figs. 1 to 6 serving to explain one embodiment and Fig. 7 a further embodiment.

In detail Figures 1-4 show the circuit arrangements of semi-automatic subsidiary exchanges whose calls are set up by means of the switching means shown in Fig. 5 at an operator's position in a main exchange HA. Fully automatic subscribers also have access to the semi-automatic network. The general arrangement of the system as a whole is shown in Fig. 6. This will be described first.

It can be seen from this figure that the subsidiary exchanges U1-U4 are connected in series and have access to a main exchange HA in which the setting up of calls between the individual subscribers of these subsidiary exchanges or to other exchanges can take place. The arrangement constitutes a semi-automatic system. A fully automatic system is also connected to the main exchange HA, the subscribers of which system set up both their internal calls and also their calls to the individual subsidiary exchanges automatically by means of the usual setting of switches without making use of the exchange operator.

The circuit arrangements of the individual subsidiary exchanges is such that in the exchange U1 there is provided a link comprising a call finder and a final selector. This is connected by way of a connecting line with the exchange U2 in which there is also a finder-connector link. Between the exchange U2 and the next exchange U3 there is another connecting line, but in the exchange U3 there are two finder-connector links which are correspondingly connected to the exchange U4 over two connecting lines. The exchange U4 like the exchange U3 possesses two finder-connector links. Two connecting lines, only one of which is shown with a repeater lead from this exchange to the main exchange HA.

The number of connecting lines and finder links can of course be differently chosen in accordance with the traffic to be handled. If desired secondary switches can be arranged between the links and connecting lines.

The establishment of any call required by a subscriber of the semi-automatic system is effected, as already stated, by means of the operator in the main exchange HA, the connecting lines seized by the calling subscriber insofar as they are in the appropriate traffic direction being used by the operator for setting up the desired connecting path when the call is to a subscriber of the same subsidiary exchange or group of exchanges. The lines which are not required after establishment of the connecting path are released so as to be available for the establishment of other calls.

If subscriber Tn1, for example, of the exchange U1 makes a call the latter is extended over the individual connecting lines joining the subsidiary exchanges to the operator in the main exchange. If the operator wishes to deal with the call immediately she carries out a switching measure after having plugged the jack AK which causes the call finder in the individual exchanges to be set on that connecting line over which the call-

ing signal passed from exchange to exchange and so to the operator. By this means it is possible not to have the connecting path over the said exchanges to the operator blocked as soon as a subscriber initiates a call. In this way the operator if she wants to set up a call herself in the semi-automatic system is not prevented from doing so by any call which may have been received. Similarly full automatic subscribers can dial into the semi-automatic system while calls from subscribers of the semi-automatic system are present provided that the operator has not yet dealt with these. These two possibilities are of special advantage in semi-automatic systems in which calls from subscribers are registered since after the release of a previous call other registered calls do not immediately block the connecting path to the main exchange, so that the operator or subscribers of the fully automatic system can dial into the semi-automatic system.

The details of these operations will be appreciated from the following description.

Establishment of a call within the semi-automatic system (Figs. 1-6)

The establishment of a call between subscribers T_{n1} and T_{n2} of the subsidiary exchange U_1 will first be described. Without taking up his receiver subscriber T_{n1} operates his magneto and thereby influences relay A over its winding I and the subscriber's loop. By closing contact $1a$ relay A locks up over winding II in a circuit which passes over: earth, battery, contacts $1a$ and $2c$, winding II of relay A, resistance W_{12} , relay A_n and earth. If the connecting link of the exchange U_1 is free the following circuit is set up after relay A_n has energized in the locking circuit of relay A: earth, battery, relay M_{t1} , contacts $12h_1$, $10p_1$, $9c_{10}$, wiper lw_5 in the rest position, contact $7an$ and earth. In this circuit relay M_{t1} energizes and inter-alia supplies a battery potential over contact $42mt_1$ to lead a_1 of the connecting line leading to the exchange U_2 . In consequence the following circuit is completed: earth, battery, contacts $40c_{10}$, $42mt_1$, lead a_1 , (Fig. 2) contacts $10id_2$ and $102c_2$, winding I of relay A_2 and earth. The following circuit is also completed in the exchange U_1 (Fig. 1): earth, battery, relay H_1 , contacts $14mt_1$, $10p_1$, wiper lw_5 of the final selector LW_1 in the rest position, contact $7an$, and earth. Relay H_1 locks up by closing contacts $8h_1$ and $13h_1$. Relay M_{t1} deenergizes through the opening of contact $12h_1$. Accordingly the circuit for relay A_2 passing over the A_1 lead is also broken at contact $42mt_1$. Relay A_2 (Fig. 2) remains energized, however, since it has meanwhile locked up over its winding II in the circuit: earth, battery, winding II of relay A_2 , contacts $104a_2$, $105c_2$, $106d_2$ and earth.

If the finder link in exchange U_2 is free the following circuit is set up when relay A_2 energizes: earth, battery, relay M_{t2} , contacts $107h_2$, $115p_2$, $113c_{20}$, wiper lw_5 of the final selector LW_2 in the rest position, contact $112a_2$ and earth.

Relay M_{t2} energizes in this circuit and sets up the following circuit by closing contact $143mt_2$: earth, battery, contacts $141c_{20}$, $143mt_2$, lead a_2 of the connecting line to the exchange U_3 (Fig. 3), contacts $201d_3$, $202c_3$, winding I of relay A_3 , battery and earth. Relay A_3 energizes in this circuit. Meanwhile the following circuit has been set up in the exchange U_2 (Fig. 2) through the closing of contact $109mt_2$: earth, battery, relay H_2 , contacts $109mt_2$, $115p_2$, $113c_{20}$, wiper lw_5 of the final selector LW_2 in the rest position, con-

tact $112a_2$ and earth. In this circuit relay H_2 energizes and locks up by closing contacts $108h_2$ and $114h_2$. Relay M_{t2} is deenergized by the opening of contact $107h_2$ so that the circuit for relay A_3 is broken at contact $143mt_2$. Relay A_3 does not release because meanwhile it has locked up over its winding II: (Fig. 3) earth, battery, winding II of relay A_3 , contacts $204a_3$, $205c_3$, $206d_3$, and earth.

If one of the finder links in the exchange U_3 is free, for example, that comprising the call finder AS_3 and the final selector LW_3 , the following circuit is completed: earth, battery, relay H_3 , contact $217p_3$, wiper ew_1 of the setting switch EW_3 in the rest position, contacts $213c_{30}$, $210a_3$ and earth. Relay H_3 energizes in this circuit and completes the following circuit over its contact $243h_3$: earth, battery, contacts $243h_3$, $245h_4$, lead a_3 of the connecting line to exchange U_4 (Fig. 4), contacts $301d_4$, $302c_4$, winding I of relay A_4 , battery and earth. Relay A_4 energizes in this circuit. Meanwhile relay H_4 has been operated in exchange U_3 over contact $220h_3$. It holds relay H_3 energized over contact $211h_4$. The circuit for relay A_4 is broken by the opening of contact $254h_6$. Relay A_4 (Fig. 4) holds up, however, over its winding II in the circuit: earth, battery, winding II of relay A_4 , contacts $304a_4$, $305c_4$, $306d_4$ and earth.

If one of the links in the exchange U_4 , for example, that comprising the call finder AS_4 and the final selector LW_4 is free the following circuit is completed: earth, battery, relay H_5 , contact $316p_4$, wiper ew_1 of the setting switch EW_4 in the rest position, contacts $313c_{40}$, $310a_4$ and earth. Relay H_5 energizes in this circuit and completes the following circuit over its contact $339h_5$: earth, battery, contacts $339h_5$, $342h_6$, lead a_4 to the main exchange HA (Fig. 5), contacts $405c_5$ and $407c_{50}$, winding I of relay A_5 and earth. Relay A_5 energizes in this circuit. Meanwhile relay H_6 has operated in the exchange U_4 (Fig. 4) through the closing of contact $319h_5$ and now holds relay H_5 energized over contact $314h_6$. The energizing circuit for relay A_5 is broken by the opening of contact $342h_6$. Relay A_5 (Fig. 5) locks up in the following circuit over its winding II: earth, battery, winding II of relay A_5 , contacts $414a_5$, and $416h_7$ and earth. Moreover, the closing of contact $415a_5$ lights up the call indicating lamp AL at the operator's position.

From the above description it will be understood that the call from subscriber T_{n1} is stored in the individual exchanges U_1-U_4 and is indicated by the lighting of a lamp at the main exchange HA without the call finders AS_1-AS_4 in the individual exchanges having been set. Thus there is no blocking of the individual lines between the subsidiary exchanges so that these connecting lines can be used for example for the establishment of an incoming call by the operator or by fully automatic subscribers over the main exchange HA . This will be later described in detail.

Had the finder link of the exchange U_1 been in use when the subscriber T_{n1} made his call relay M_{t1} would not have energized since then wiper lw_5 of the final selector LW_1 would have left its normal position and contacts $9c_{10}$ and $10p_1$ would be open. The call would only be registered by delay A remaining energized over winding II in series with relay A_n so as to be transmitted to relay M_{t1} by contact $7an$ when the link became free and then to energize relay A_2 .

in the next exchange U2 and so to extend the call as already described.

If the link in the exchange U2 (Fig. 2) had been engaged relay Mt2 would not have energized after the energizing of relay A2 since the wiper *lw5* of the final selector LW2 would have been away from the normal position and the contacts 113c20 and 115p2 open. The call from the exchange U1 would be registered, however, by the continued energization of relay A2. It would be extended to the next exchange U3 as soon as the link became free. If in the latter exchange the link comprising the call finder AS3 and the final selector LW3 is busy the starting chain is switched over to the next link through the closing of contact 212c30. The call initiating impulse then operates on this link. Only if this is also engaged no call is initiated at first. The call, however, remains registered by the continued energization of relay A3 so that it can become effective when a link becomes free and the call can be extended to the next exchange U4.

Corresponding operations take place in the exchange U4 where a call is similarly switched over to the second link in the event of the link shown comprising the call finder AS4 and the final selector LW4 and is registered (relay A4 held energized) if the second link is busy so that the call can be extended to the main exchange HA when a link becomes free. The call is thus not lost.

If now the operator wishes to deal with a call she inserts her answering plug ASt in the answering jack AK. Relay C50 is thus energized over: earth, battery, relay C50, jack springs, plug, resistance *W114* and earth. Through the closing of contact 425c50 the following circuit is set up: earth, battery, resistance *W113*, contact 425c50, relay H7, and earth. Relay H7 energizes. The opening of contact 416h7 opens the locking circuit of winding II of relay A5 and also extinguishes the call indicating lamp AL. The opening of contact 429h7 prevents the repeater Ue from being seized by a group selector GW of the fully automatic portion of the system. Meanwhile the following circuit has been completed after the energizing of relay C50: earth, battery, choke-coil Dr9, contacts 404j5 and 402c50, lead *a4* of the connecting line to the exchange U4 (Fig. 4), contact 341h6, relay J4 and earth. Relay J4 energizes in this circuit. Through the closing of contact 349j4 and the opening of contact 353j4 relay C40 becomes energized in the following circuit: earth, battery, relay C40, contact 349j4 and earth. Relay C40 locks up by closing contact 351c40.

In order to set the call finder in the exchange U4 the operator now actuates the answering key (Ab1 and Ab2) and her ringing key R. The following circuit is set up: earth, battery, ringing key R, answering key Ab1, plug and jack, contact 412c5, relay B5, contact 413s5 and earth. Relay B5 energizes in this circuit and by closing contact 409b5 enables the following circuit to be set up: earth, battery, choke-coil Dr10, contact 409b5, lead *b4* of the connecting line to the exchange U4 (Fig. 4), contact 344y4, relay E4 and earth. In this circuit relay E4 energizes. The following circuit is completed through the closing of contact 317e4: earth, battery, rotary magnet DAS4 of the call finder AS4, contact 320r4, contact 318das4 of the rotary magnet DAS4, contacts 317e4, 316p4, wiper *ew7* of the setting switch EW4 in the rest position, contacts 314h6, 310a4 and earth. The rotary magnet DAS4 of

the call finder AS4 energizes in this circuit. Through the opening of contact 318das4 in the energizing of the magnet DAS4 relay R4 is energized. It breaks the operating circuit for the rotary magnet DAS4 at contact 320r4 so that the magnet deenergizes and closes its contact 318das4 again. Relay R4 is thus short-circuited and the same operations are repeated. Through the interaction between the two switching means the call finder AS4 is stepped until it reaches the contact marked over contact 324a4 by the call. The following circuit is now set up: earth, battery, relay C4, contact 324a4, wiper *as3* of the call finder AS4, windings I and II of relay P4, contact 327h5 and earth. In this circuit relays P4 and C4 energize. The opening of contact 316p4 prevents the further stepping of the call finder AS4. The speaking leads are switched through at contacts 328p4 and 329p4, while the seized line is guarded by short circuiting winding II of relay P4 at contact 326p4. After the opening of contact 316p4 relay H5 deenergizes and by opening contact 319h5 disconnects relay H6. When relay C4 energizes in the testing circuit the locking circuit for winding II of relay A4 is broken by the opening of contact 305c4 and also winding I of relay A4 is disconnected at contact 302c4. The opening of contact 309c4 removes the short-circuit about winding I of relay D4. Meanwhile after the setting of the call finder AS4 and the energizing of relay P4 the following circuit has been set up: earth, battery, relay Q4, wiper *as4* of the call finder AS4, wiper *ew3* of the setting switch EW4 in the rest position, contact 321p4 and earth. In this circuit relay Q4 energizes so that through the closing of contact 327q4 the following circuit is set up: earth, battery, rotary magnet DLW4 of the final selector LW4, contacts 351q4, 356h40, 355p40 and earth. The final selector takes one step forward. Wiper *lw6* of the final selector LW4 thus passes on to the contact segment. On the energizing of the rotary magnet DLW4, relay H40 is energized by contact 363dlw4 so that the energizing circuit of the rotary magnet DLW4 is opened. Through the interaction between relay H40 and the rotary magnet DLW4 the final selector LW4 is stepped until wiper *lw5* reaches the marked contact 1 which is marked over contact 325q4 and wiper *as5* of the call finder AS4. As soon as this happens relay H40 is held energized over: earth, battery, relay H40, wiper *lw5* of the final selector LW4, contact 1, wiper *as5* of the call finder AS4, contact 325q4, and earth. Any further stepping of the final selector LW4 is prevented by the continued opening of contact 356h40.

Meanwhile the following circuit has been closed: earth, battery, choke-coil Dr7, contacts 338u4, 337c40, 336k4, 381u4, 328p4, wiper *as1* of the call finder AS4, the *a3* lead of the connecting line to the exchange U3 (Fig. 3), contact 244h4, relay J3 and earth.

After the speaking leads have been switched through the following circuit is also set up (Fig. 4) earth, battery, resistance *W115*, contacts 371e4, 334k4, 382u4, 329p4, wiper *as2* of call finder AS4, lead *b3* of the connecting line to the exchange U3 (Fig. 3), contact 247y3, relay E3, and earth.

After relay J3 has energized over the *a3* lead relay C30 becomes energized in the exchange U3 (Fig. 3) after contact 254j3 has been closed and contact 257j3 opened. Relay C30 locks up by closing contact 255c30.

Through the energizing of relay E3 over lead 75

b3 the following circuit is closed: earth, battery, rotary magnet DAS3 of the call finder AS3, contacts 216r3, 219das3 of the rotary magnet DAS3, contacts 218e3 and 217p3, wiper ew1 of the setting switch EW3 in the rest position, contacts 211h4 and 210a3 and earth. In this circuit the rotary magnet DAS3 of the call finder AS3 energizes so that the call finder takes a step forward. The opening of contact 219das3 switches 5 on relay R3 which at contact 216r3 breaks the energizing circuit for the magnet DAS3. Through the closing of contact 219das3 when the magnet releases relay R3 is caused to deenergize. This inter-action is repeated until the connecting line seized by the subscriber is found. Then 10 the following circuit is set up: earth, battery, relay C3, contact 223a3, wiper as3 of the call finder AS3, windings I and II of relay P3, contact 230h3 and earth. In this circuit relays C3 and 15 P3 energize. The opening of contact 217p3 prevents any further influencing of the rotary magnet DAS3. Moreover the relay H3 releases so that relay H4 also releases due to the opening of contact 220h3. The speaking leads are switched 20 through at contacts 226p3 and 227p3.

The locking circuit of winding II of relay A3 is broken at contact 205c3 through the energizing of relay C3 in the testing circuit, and at contact 207c3 the short-circuit about winding I of 25 relay D3 is removed.

Meanwhile the following switching operations have taken place following the energizing of relay P3: at contact 232p3 winding II of relay P3 is short-circuited for guarding purposes; at contact 221p3 relay Q3 is energized over: earth, battery, relay Q3, wiper as4 of the call finder AS3, wiper ew3 of the setting switch EW3 in the rest position, contact 221p3 and earth, so that the closing of contact 249p3 completes the following circuit: earth, battery, rotary magnet DLW3 of the final selector LW3, contacts 249q3, 251h30, 250p30 and earth. The final selector LW3 takes a step forward. Through the closing of contact 271dlw3 of the final selector LW3 relay 40 H30 is energized and this breaks the energizing circuit of the rotary magnet at contact 251h30. Through the inter-action between the rotary magnet DLW3 and relay H30 the final selector is advanced step-wise until wiper lw5 of the final 45 selector LW3 reaches the contact 1 marked by contact 225q3 over wiper as5 of the call finder AS3. Over this circuit relay H30 is then held energized so that any further stepping of the final selector LW3 is prevented by the permanent 50 opening of contact 251h30.

Meanwhile the following circuit is set up over lead a2 through the closing of contact 226p3 after the energizing of relay P3: earth, battery, choke-coil Dr5, contacts 231u3, 236c30, 235k3, 228u3, 55 226p3, wiper as1 of the call finder AS3, lead a2 of the connecting line to the exchange U2 (Fig. 2), contact 142mt2, relay J2 and earth. Moreover after the closing of contact 227p3 the following circuit is set up over the lead b2: earth, battery, resistance Wi6, contacts 279e3, 238k3, 229u3 and 227p3, wiper as2 of the call finder AS3, lead b2 of the connecting line to the exchange U2 (Fig. 2), contact 154y2, relay E2 and earth.

70 On account of the energizing of relay J2 over lead a2 the relays C2 and C20 are energized over contact 160j2.

The energization of relay E2 over lead b2 causes contact 127e2 to be closed so that the following 75 circuit is set up: earth, battery, relay H20, con-

tacts 129h2, 127e2, and earth. In this circuit relay H20 energizes and by closing its contact 128h20 locks up. Through the closing of contact 110h20 the following circuit is set up: earth, battery, rotary magnet DAS2 of the call finder, 5 contact 116r2, contact 111das2 of the rotary magnet DAS2, contacts 110h20, 115p2, 114h2, wiper lw5 of the final selector LW2, contact 112a2 and earth. In this circuit the rotary magnet DAS2 energizes so that the call finder AS2 takes a step 10 forward. Through the opening of contact 111das2 relay R2 energizes in the above circuit and by opening contact 116r2 disconnects the rotary magnet DAS2. The interaction between relay R2 and the rotary magnet DAS2 causes the 15 call finder AS2 to be stepped forward until it reaches the connecting line seized by the calling subscriber. The following circuit is then set up: earth, battery, relay C2, contact 120a2, wiper as3 of the call finder AS2, windings I and II of 20 relay P2, contacts 124h2, 125h20, 126p20, contact 121e2 or 122c20 or wiper lw6 of the final selector LW2 in the rest position and earth. In this circuit relays C2 and P2 energize. Through the opening of contact 115p2 any further stepping of 25 the call finder AS2 is prevented. Through the closing of contacts 130p2 and 131p2 the speaking leads are switched through while the high resistance winding II of relay P2 is short-circuited by the closing of contact 123p2. Through the 30 opening of contact 115p2 relay H2 is deenergized and by the opening of contact 129h2 relay H20 is deenergized.

On the energizing of relay C2 winding II of 35 relay A2 is disconnected by the opening of contact 105c2 and through the opening of contact 102c2 winding I of relay A2 is disconnected.

Meanwhile through the closing of contact 130p2 the following circuit has been set up: earth, battery, relay X2, contacts 137c20, 181b2, 186u2 and 40 130p2, wiper as1 of the call finder AS2, lead a1 of the connecting line to the exchange U1 (Fig. 1), contact 41mt1, relay J1 and earth.

Moreover through the closing of contact 131p2 the following circuit is completed: earth, battery, 45 resistance Wi4, contacts 152h20 or 150e2 and 151h20, 145w2, 135k2, 134b2, 187u2, 131p2, wiper as2 of the call finder AS2, lead b1 of the connecting line to the exchange U1 (Fig. 1), contact 52y1, relay E1 and earth.

In the circuit passing over lead a1 relay J1 (Fig. 1) in the exchange U1 and relay X2 (Fig. 2) in the exchange U2 energize. Through the energizing of relay J1 in the exchange U1 contact 56j1 is closed, so that relays C1 and C10 energize. Relay E1 is energized in the circuit completed over the b1 lead and by closing contact 18e1 energizes 55 relay H10. Through the closing of contact 111h10 the following circuit is set up: earth, battery, rotary magnet DAS1 of the call finder AS1, contacts 16r1 and 15das1 of the rotary magnet DAS1, contacts 11h10, 10p1 and 8h1, wiper lw5 of the final selector LW1 in the rest position, contact 1an and earth. In this circuit the rotary magnet energizes, advances the switch one step and energizes relay R1 so that by the well known inter- 60 action between the two switching means the call finder AS1 is stepped till it reaches the called subscriber's line. The following circuit is then completed: earth, battery, relay C, contact 5a, wiper as3 of the call finder AS1, windings I and II of relay P1, contacts 25h1, 24h10 and 23p10, contacts 20e1 or 21c10 or the wiper lw6 of the final selector LW1 in the rest position, and earth. In this circuit relays C and P1 energize. Through the 65

70 circuit the relays C and P1 energize. Through the 75

opening of contact $2c$ the locking circuit for winding II of relay A and the energizing circuit for relay A_n are broken. When relay $P1$ energizes any further stepping of the final selector $AS1$ is prevented by the opening of contact $10p1$. Moreover relay $H1$ deenergizes and by opening contact $19h1$ deenergizes relay $H10$. The speaking leads are switched through at contacts $26p1$ and $27p1$, and the high resistance winding II of relay $P1$ is short-circuited by the closing of contact $22p1$.

If the ringing key R is still depressed by the operator in the main exchange HA , battery potential is applied to the b -lead from exchange to exchange so that the corresponding E -relays are still operated. Relay $E1$ energized in the exchange $U1$ enables the following circuit to be set up if the calling subscriber has not remained at his station: earth, battery, resistance $W1$, relay $W1$, contact $74e1$ and earth. Through the closing of contact $44w1$ the subscriber is called back to his station. When he replies after the ringing key has been released and all the E -relays in the subsidiary exchanges have been released, among these relay $E1$ in the exchange $U1$, the following circuit is set up: earth, battery, relay $X1$, contacts $30c10$, $29b1$, $27p1$, wiper $as1$, subscriber $Tn1$, wiper $as2$, contacts $26p1$, $34b1$, $35h1$, relay $Y1$, and earth. The further transmission of ringing current is prevented. Over contact $53y1$ and the choke-coil $Dr1$ battery potential is applied to the $b1$ lead and energizes relay $Y2$ in the subsidiary exchange $U2$ which now applies battery to lead $b2$ over contact $153y2$ and the choke-coil $Dr4$. This influences relay $Y3$ in the exchange $U3$ which applies battery to lead $b3$ over contact $246y3$ and the choke-coil $Dr6$. Relay $Y4$ therefore energizes in the exchange $U4$ and extends battery over lead $b4$ to the main exchange HA over contact $343y4$ and the choke coil $Dr8$. Since relay $B5$ in the main exchange has released after the restoration of the ringing key winding I of relay $S5$ is connected up over contact $408b5$. On account of the closing of contact $419s5$ the clearing signal lamp SL lights up indicating to the operator that the subscriber has replied. The operator can now make her inquiry.

If the subscriber $Tn1$ wishes to call the subscriber $Tn2$ of his own subsidiary exchange $U1$, the operator now dials the digits characterizing the connecting lines leading to the individual subsidiary exchanges. Contact $ns1$ is therefore closed impulsively through the operator's dialling while contact nsa remains open throughout each impulse train.

The first impulse train may comprise three impulses. Accordingly relay $J5$ is energized thrice over contact $ns1$ (Fig. 5). During this time, relay $V5$ which is slow-to-release is held energized through the intermittent closing of contact $420j5$. Corresponding to the energizing of relay $J5$ contact $404j5$ is opened three times so that the energizing circuit of relay $J4$ (Fig. 4) which passes over the lead $a4$ of the connecting line to the exchange $U4$ is broken three times. In the exchange $U4$ (Fig. 4) relay $V4$ is connected up on the first release of relay $J4$ over contacts $350j4$ and $384c40$ and being slow-to-release remains energized throughout the impulse train. Moreover, the following circuit is closed and broken again corresponding to the impulses transmitted by the operator: earth, battery, rotary magnet $DEW4$ of the setting switch $EW4$, contacts $362c40$, $358j4$, $355p40$, and earth. The rotary magnet $DEW4$ is energized three times and thus steps the setting

switch $EW4$ by three steps. In consequence its wiper $ew1$ stands on the contact already reached by wiper $lw4$ of the final selector $LW4$ so that since relay $Q4$ which is held energized over contact $322v4$ during the impulsing makes a delayed release after the impulsing and thus maintains its armature operated for some time thereafter, the following circuit is set up: earth, battery, windings II and I of relay $D4$, wiper $lw3$ of the final selector $LW4$, windings I and II of relay $P40$, contact $368v4$ (relay $V4$ is deenergized after the impulse transmission), contact $366q4$,—and in parallel therewith over earth, battery, winding III of relay $P40$, resistance $W11$,—wiper $lw4$ of the final selector $LW4$, wiper $ew1$ of the setting switch $EW4$, contact $370c40$ and earth. In this circuit relays $D4$ and $P40$ energize so that the following circuit is also completed before the release of the slow relay $Q4$: earth, battery, relay $U4$, contacts $373q4$, $371p40$, and $372c40$ and earth. Relay $U4$ now holds up over its contact $372u4$ while relay $P40$ locks up over its winding III and contact $365p40$.

It should be mentioned that relay $K4$ was energized over contact $352dew4$ when the rotary magnet $DEW4$ of the setting switch energized and then locked up over contact $347k4$ and $346y4$ of the relay $Y4$ deenergized by the opening of contact $334k4$ and wiper $ew5$ of the setting switch $EW4$ which has been moved out of the rest position. Through the closing of contact $335k4$, relay $J3$ in the exchange $U3$ is held energized: after relay $P40$ has energized and the speaking leads have been switched through at contact $374p40$ and $375p40$, the locking circuit for this relay $J3$ passes over: earth, battery, relay $X4$, contacts $331j4$ and $374p40$, wiper $lw1$ of the final selector $LW4$, lead $a3$, to the subsidiary exchange $U3$ (Fig. 3), contacts $245h4$, $242h3$, relay $J3$ and earth.

Relay $Y4$ which was previously energized on the calling party's reply and deenergized after the opening of contact $334k4$ is energized in the following circuit after the final selector $LW4$ has been set since the speaking leads in the call finder $AS4$ are open at contacts $381u4$ and $382u4$: (Fig. 3) earth, battery, choke-coil $Dr6$, contact $246y3$, lead $b3$ of the connecting line of the exchange $U4$ (Fig. 4) wiper $lw2$ of the final selector $LW4$, contact $375p40$, and $376e4$, relay $Y4$ and earth. At contact $346y4$ the locking circuit for relay $K4$ is broken.

By means of a second impulse train which may similarly comprise three impulses relay $J5$ in the main exchange HA and relay $J4$ in the subsidiary exchange $U4$ are again energized in a corresponding manner so that through the intermittent interruption at contact $331j4$ (Fig. 4) the circuit of relay $J3$ (Fig. 3) passing over lead $a3$ of the connecting line to the exchange $U3$ is correspondingly interrupted. In the exchange $U3$ relay $V3$ energizes over contact $353j3$ on the first release of relay $J3$ and remains energized on account of its slow-to-release feature during the whole impulse train. In addition the following circuit is set up: earth, battery, rotary magnet $DEW3$ of the setting switch $EW3$, contacts $262c30$, $261j3$ and $250p30$ and earth. The setting switch $EW3$ is advanced three steps. Relays $P30$ and $U3$ are influenced in dependence upon relay $Q3$ in a similar manner to that occurring in the case of exchange $U4$. Moreover, relay $K3$ has been switched on over contact $250dew3$ when the first impulse became operative and has locked up over contact $260k3$ and con-

tact 259y3 of the relay Y3 deenergized through the opening of contact 238k3. After relays P30 and U3 have been energized the following circuit for relay J2 in the exchange U2 (Fig. 2) passes over: earth, battery, relay X3, contacts 239j3 and 277p30, wiper lw1 of the final selector LW3, lead a2 to the subsidiary exchange U2 (Fig. 2), contact 142mt2, relay J2 and earth. Relay Y3 in the exchange U3, which was deenergized by relay K3 on the first impulse because of the opening of contact 238k3 energizes again over contact 278p30. After the speaking leads have been switched through relay K3 releases on account of the opening of contact 259y3.

15 The next impulse train which can similarly consist of three impulses operates in a similar manner on the relay J2 in the exchange U2 (Fig. 2) through the impulsive opening of contact 239j3 and there, in addition to the energizing of 20 the slow-to-release relays V2 and V20 over contact 159j2, causes the intermittent operation of the rotary magnet DLW2 of the final selector LW2 over: earth, battery, rotary magnet DLW2 of the final selector LW2, contacts 115c2, 176j2 25 and 183p20, and earth. The final selector LW2 is stepped forward. Through the energizing of relay V20 relay K2 has been energized meanwhile over: earth, battery, relay K2, contacts 165v20 and 163c2, and earth, so that when now relays 30 V2 and V20 release at the end of the impulse train on account of the opening of contact 159j2 the following testing circuit is set up: earth, battery, winding I of relay D2, contacts 118sp2, and wiper 117d2, wiper lw3 of the final selector LW2, winding I of relay P20, contacts 185e2, 167k2, 35 166v20 and 163c2 and earth. In this circuit relays D2 and P20 energize. Relay D2 serves to guard the connecting line, while relay P20 which locks up over its winding III after relay K2 has 40 released at the end of the impulse train causes the speaking leads to be switched through at contacts 178p20 and 179p20. In this connection it should be mentioned that when relay K2 energizes during the dialling, relay B2 is connected 45 up to the lead b1 of the connecting line over contact 133k2 and is energized over its contact 53y1 and the choke-coil Dr1 in the exchange U1 so that accordingly the locking circuit for winding III of relay P20 at first passes over: earth, battery, winding III of relay P20, contacts 180p20, 50 168b2 and 163c2, and earth. The locking circuit for relay B2 passes over contact 134b2 after relay K2 has released at the end of the impulse train. Since, however, after the energizing of relay P20, 55 relay U2 is energized over: earth, battery, relay U2, contacts 190p20 and 189p2, wiper asd of the call finder AS2, wiper lw4 of the final selector LW2, contact 188c2, and earth, on account of the setting of selector LW2 on the line seized by the 60 calling subscriber i. e., by the coincidence between the setting of the call finder AS2 and the final selector LW2, relay B2 is deenergized now through the opening of contact 187u2. Relay P20 now holds up over its winding III and contact 191u2. After the speaking leads have been 65 switched through the locking circuit for relay J1 in the exchange U1 is as follows: earth, battery, relay X2, contact 139j2 and 178p20, wiper lw1 of the final selector LW2, lead a1, in the subsidiary exchange U1, (Fig. 1), contact 41mt1, relay J1, and earth. Relay Y2, which deenergized on account of the opening of contact 135k2 when relay K2 energized is energized again at the 70 end of the impulse train and after the speaking leads have been switched through over: (Fig. 1)

earth, battery, choke-coil Dr1, contact 53y1, lead b1, call finder, (Fig. 2), wiper lw2 of the final selector LW2, contacts 179p20, 145w2, 151h20, and 149e2, relay Y2 and earth.

The next impulse train transmitted by the exchange operator may also consist of three impulses and serves to set the final selector LW1 in the exchange U1 on the wanted subscriber's line. This impulse train is transmitted over the individual subsidiary exchanges like the preceding impulse trains and operates in the exchange U1 by influencing relay J1 in a similar manner so that when relay J1 first releases an energizing circuit is produced by relays V1 and V10 over contact 57j1. These relays remain energized 15 throughout the impulse train through being slow-to-release. The rotary magnet DLW1 of the final selector LW1 is influenced over contact 71j1. On the first impulse moreover relay K1 is energized over: earth, battery, relay K1, contacts 77v10, and 58c1 and earth. Through the closing of contact 32k1 relay B1 is connected to the lower speaking lead and is energized over the loop of the calling subscriber Tn1, contacts 29b1 and 30c10, relay X1 and battery. Since now 20 relay Y1 is disconnected from the subscriber's loop through the opening of contact 35k1 it releases and by disconnecting the battery potential over choke coil Dr1 at contact 53y1 deenergizes relay Y2 in the exchange U2. In a corresponding 25 way the Y-relays at all the other subsidiary exchanges deenergize so that the clearing signal lamp SL in the main exchange is extinguished. Through the opening of contact 29b1 relay X1 which was held energized over the calling subscriber's loop releases.

If the wanted subscriber Tn2 is free the following circuit is established after relay V10 has deenergized at the end of the impulse train and before relay K1 has deenergized: earth, battery, 40 relay CO, wiper lw3 of the final selector LW1, winding I of relay P10, contacts 79e1, 78k1, 76v10 and 58c1 and earth. Relay P10 energizes and locks up over its winding III in a circuit over earth, battery, winding III of relay P10, contacts 45 62p10, 63b1 and 58c1 and earth. By depressing the ringing key R the operator now causes relay E1 to be energized in the subsidiary exchange U1 in that the E-relays in the individual exchanges are operated in succession so that over contact 50 74e1 relay W1 energizes and ringing current can be transmitted to the wanted subscriber Tn2 over the operated contact 44w1. The transmission of ringing current can also take place automatically. In this case the operation of relay E1 55 is not necessary but instead a five seconds switch is brought into operation. When the wanted subscriber Tn2 replies relays X1 and Y1 are influenced over his loop during a pause in the ringing so that now by the application of a battery 60 potential to the b-lead over the various contacts of the Y-relays the clearing signal lamp SL is lit up in the main exchange HA in the same way as has been described above in connection with the reply of the calling subscriber. The subscribers 65 can now converse together.

Since the links in the subsidiary exchanges U2, U3, and U4 are not required for the conversation between subscribers Tn1 and Tn2 they are now released through the operator withdrawing her 70 plug. Relay C50 in the main exchange first releases so that relay H in the main exchange de-energizes through the opening of contact 425c50 and then releases the repeater Ue (429h7). Through the opening of contact 402c50 battery 75

potential is disconnected from lead *a4* of the connecting line to the exchange *U4* so that relay *J4* in the exchange *U4* (Fig. 4) deenergizes. Through the closing of contact *353j4*, relay *C40* is short-circuited so that it releases its armature. In dependence upon the deenergizing of relays *J4* and *C40* the devices in the subsidiary exchange *U4* are now released in a manner with which we are not concerned, the final selector *LW4* being first restored to normal and then the setting switch *EW4* so that after the restoration to normal of wiper *ew1* the link can be seized afresh. Since on account of the opening of contact *331j4* battery potential is removed from lead *a3* relay *J3* in the exchange *U3* releases with the result that relay *C30* deenergizes through the closing of contact *257j3*. Thus all the devices in the exchange *U3* are also released. Similar switching operations take place through the deenergizing of relay *J2* in the exchange *U2* (Fig. 2). First relay *V2* is operated over contact *159j2* so as to short-circuit relay *C2* at contact *162v2* so that this relay deenergizes and then also relay *C20*. The link in the exchange *U2* is then released. In the exchange *U1* relay *J1* deenergizes through battery being disconnected from lead *a1* of the connecting line (Fig. 2: contact *139j2*). Since, however, in this exchange relay *B1* is energized over the loop of the calling subscriber *Tn1* the following energizing circuit obtains for relay *S1*: earth, battery, relay *S1*, contacts *65b1*, *64k1*, *62p10*, *63b1*, and *58c1* and earth. Through the closing of contact *67j1* when relay *J1* releases relay *V1* energizes but relay *C1* is short-circuited over contact *60v1* since contact *59s1* is open, consequently the link in the exchange *U1* remains set so that the established connection is maintained. In order to guard this link against seizure for example over leads *a1* and *b1* the following circuit is closed: earth, battery, choke-coil *D1*, contact *53y1*, lead *b1* of the connecting line to the exchange *U2* (Fig. 2) relay *Sp2*, contacts *103a2*, *105c2* and *106d2* and earth. Relay *Sp2* is energized in this circuit and while removing the short-circuit from winding *II* of relay *D2* at contact *113sp2* guards the connecting line leading to the exchange *U1* and thus also the link in the exchange *U1* against seizure.

When the conversation between subscribers *Tn1* and *Tn2* is finished relays *B1*, *X1* and *Y1* deenergize when the receiver has been replaced so that at first through the opening of contacts *63b1* and *65b1* relays *S1* and *P10* deenergize. Through the short-circuiting of relay *C1* over contacts *59s1* and *60v1*, relay *C1* releases and through the opening of contact *58c1* relay *C10* deenergizes. The further process of the release is of no particular interest.

Calls between subscribers of different subsidiary exchanges in the semi-automatic network can now be set up in a corresponding manner. In this case also the connecting path not used for conversation between the two subscribers is released by the operator withdrawing the plug.

Establishment of an incoming call

If in contrast with the operations described above the operator wishes to set up an incoming call and not to attend to a call which is received in the main exchange from the subscriber *Tn1* she inserts only the answering plug *AS1* in the jack and switches over her enquiry switch but does not carry out the actuation of the ringing key which is otherwise necessary. Relay *C50* is again energized and by closing contact *402c50*

applies a battery potential to lead *a4* so that relay *J4* in the exchange *U4* is influenced as above. The call finder *AS4* does not become set since relay *E4* is not energized. The closing of contact *349j4* causes the energization of relay *C40* which locks up over contact *351c40*.

When the operator transmits two impulses by means of her dial switch, relay *J4* is intermittently deenergized through the intermediary of relay *J5* as described above. The rotary magnet *DEW4* of the setting switch *EW4* is operated over contacts *352c40* and *358j4*. Moreover, relay *V4* is energized during the impulse trains. When this relay releases after the impulse train an automatic impulsing circuit for the rotary magnet *DLW4* of the final selector *LW4* is set up over earth, battery, rotary magnet *DLW4*, contacts *359x4*, *360v4*, wiper *ew4* of the setting switch *EW4*, wiper *lw6* of the final selector *LW4*, contacts *356h40* and *355p40* and earth. When the final selector *LW4* has reached the contact marked by wiper *ew1* of the setting switch *EW4* the following circuit is set up assuming the setting switch to be set on contact 2: earth, contact *310c40*, wiper *ew1* of the setting switch *EW4*, contact 2, contact *367q4*, winding *I* of relay *P40*, wiper *lw3* of the final selector *LW4* and over the wanted subscriber's circuit which is not shown, to battery and earth. If the subscriber is free relay *P40* energizes in the known way. The final selector *LW4* is brought to rest through the opening of contact *355p40*, the speaking leads are switched through and ringing current is transmitted and is adapted to be disconnected when the wanted subscriber replies in the same way as was described in connection with the exchange *U1* so that the call to the wanted subscriber is established. The calling impulse of the subscriber *Tn1* of the exchange *U1* which was described in the previous section is taken up by relay *A4* and which has led to the energizing of relays *H5* and *H6* is rendered inoperative as regards the link *AS4/LW4* when an incoming call is set up by the operator during the opening of contact *313c40*. After the deenergizing of relays *J5* and *H6* it passes to the second link *AS4'/LW4'* (Fig. 6), and the call registering is of course maintained in this case in the exchange *U4*.

It would be different if the final selector *LW4* had not been set by the operator on a subscriber of the exchange *U4* but on the connecting line *a3/b3* to the exchange *U3*. In this case the locking circuit of winding *II* of relay *A4* would have been disconnected by the energizing of relay *D4*, so that the registration of the call in the exchange *U4* would have been terminated. In the exchange *U3* relay *J* would have been energized again after the connecting line had been switched through and would have energized relay *C30* so that the calling impulse of subscriber *Tn1* would have been rendered ineffective as regards the link *AS3/LW3* by the opening of contact *213c30*. The registration of the calling impulse would be maintained, however, by the continued energization of relay *A3* in the event of the final selector *LW3* being set on a subscriber's line. Alternatively, for example, if the final selector *LW3* had been set on the connecting line *a2/b2* to the exchange *U2* the relay *D3* energized in the testing circuit would have broken the locking circuit of relay *A3* at contact *206d3*. In this case the registration of the call of the calling subscriber *Tn1* in the exchange *U2* would be maintained over winding *II* of relay *A2*. If, furthermore, the operator had

set the final selector LW2 on the connecting line a1/b1 to the exchange U1 relay D2 energized in the testing circuit would have terminated the registration in the exchange U2 and the call 5 would now be registered only in the exchange U1. The call of subscriber Tn1 remains registered as long as it has not been attended to.

It can thus be seen that a subscriber's call 10 remains registered as far as that subsidiary exchange in which the final selector is no longer set by the operator on a connecting line to the preceding subsidiary exchange for the purpose of setting up an incoming call.

In the other exchanges the call becomes operative 15 immediately after the connecting path has been released without any further measure on the part of the subscriber in that if for example an incoming call has been established by the operator to a subscriber of the exchange U1 the calling signal is transmitted from subsidiary exchange to subsidiary exchange until the main exchange is reached as soon as the call has been released in the manner set out in the previous paragraph.

25 When the operator removes the plug all the connecting devices are restored in a manner which will not be described here in detail. Since in the exchange U1, relay A is held energized, relay An is also energized, so that relay Mt1 energizes over contact 7an in the exchange U1 and transitorily applies battery potential to the lead a1 by closing its contact 42mt1 so that relay A2 is energized over its winding I in the subsidiary exchange U2 and locks up over its winding II.

30 Through the closing of contact 112a2 relay Mt2 is energized in the subsidiary exchange U2 so that battery is connected transitorily to lead a2 over contact 143mt2. Consequently relay A3 energizes in exchange U3 and locks up over its winding II so that after relay H3 has been operated battery potential is applied transitorily to lead a3 over contact 243h3 for the purpose of influencing relay A4 in the exchange U4. This relay also energizes and locks up over its winding II. Relay H5 is influenced by the closing of contact 310c4 and now by applying battery potential transitorily to lead a4 over its contact 339h5 energizes relay A5 in the main exchange. This locks up over its winding II and lights up the call indicating lamp AL.

A corresponding repetition of the call initiating impulse would take place if the registering of the impulse had been maintained as far as any of the exchanges U2, U3 or U4. All the operations 55 described in this connection take place not only in the case of a call from the exchange U1, but also in the case of calls from the other subsidiary exchanges. Thus after the release of the incoming call and irrespective of which subsidiary exchange has had the registration of the call neutralized and irrespective of the particular subsidiary exchange from which the call originates, the call initiating impulse is repeated without any action 60 on the part of the calling subscriber.

65 *Establishment of a call by a fully automatic subscriber over the group selector GW'*

If a subscriber of the fully automatic system dials into the semi-automatic system while a call 70 initiating impulse is registered he first sets the group selector GW' on the repeater Ue. Since the repeater Ue itself is not blocked by a call which is registered the group selector tests on lead c. Relay C5 energizes. Through the opening of contact 426c5 relay C50 energizes. Relay

H7 energizes over contacts 424c5 and 425c50 and breaks the locking circuit for relay A5 at contact 416h1 and disconnects the call indicating lamp AL. Meanwhile battery potential has been applied to lead a4 to the subsidiary exchange U4 over contact 402c50 so that in this exchange relay J4 energizes and occasions the same switching operations as are brought about when the operator plugs in. The calling subscriber can now set up a call in a similar way to the exchange 10 operator since being a fully automatic subscriber he is equipped with a dial switch. He dials into the semi-automatic system by operating relay J5 and sets the individual final selectors of the subsidiary exchanges on the lines leading to the 15 wanted subscriber in the same way as the operator. The call registration in the individual exchanges is neutralized in the same way as has been described when the operator sets up an incoming call.

20 Thus it can be seen that fully automatic subscribers can dial into the semi-automatic system so long as there are no calls registered which have not been attended to by the operator.

When the connection between a fully automatic and a semi-automatic subscriber is released, this taking place in the same way as when the operator withdraws the plug, the call initiating impulse is repeated, at the operator's position just as occurs after the release of an incoming 30 call set up by the operator.

Fig. 7 represents a further embodiment and represents a variation of the circuit for the call 35 finder AS4 provided in the subsidiary exchange U4, this being here denoted as AS6. Only those parts which are concerned with the call finder are represented in this figure. The remaining parts correspond to the circuits shown in Fig. 4.

40 From this figure it will be seen that when the call initiating impulse comes from the preceding exchange U3 over lead a3 is received relay A6 is energized. It locks up over its winding II by closing contact 504a6. If the link comprising the call finder and final selector is free the following 45 circuit is set up: earth, battery, relay H8, contacts 511p6, wiper ew7 of the setting switch (not shown, compare Fig. 4), thermo-contact 525th1, contact 510a6 and earth. In this circuit relay H8 energizes and closes the following 50 circuit at contact 512h8: earth, battery, resistance W11, contact 514das6 of the rotary magnet DAS6 of the call finder AS6, contacts 512h8, 511p6, wiper ew7 of the setting switch, thermo-contact 525th1, contact 510a6 and earth. In parallel with the resistance W11 in the said 55 circuit there is connected the rotary magnet DAS6 of the call finder AS6 over contact 513r6. The rotary magnet DAS6 energizes and advances the call finder by one step. Through the opening of contact 514das6 during this energization 60 relay R6 is energized and disconnects the rotary magnet DAS6 at contact 513r6. By means of the interaction between relay R6 and the rotary magnet DAS6 the call finder AS6 is advanced by steps until it reaches the calling line. 65

The following circuit is then set up: earth, battery, relay C6, contact 515a6, wiper as3 of the call finder AS6, windings I and II of relay P6, contacts 527h8 and 528c40 and earth. In this 70 circuit relays C6 and P6 energize and bring about switching operations already described in connection with the corresponding relays in Fig. 4. The difference is in this case that the following circuit is established through the closing of contact 518p6: earth, battery, relay Q4, wiper AS4 of 75

the call finder AS6, wiper $ew3$ of the setting switch (shown in Fig. 4) contact $518p6$ and earth. On account of the energizing of relay Q4 at the associated final selector which is connected similarly to the final selector LW4 in Fig. 4 is stepped forward until it has reached the contact characterized by wiper AS5 of the call finder AS6.

Meanwhile a battery potential has been applied to lead $a4$ over contact $523p6$ after the energizing of relay P6 and this brings about the switching operations in the main exchange HA (Fig. 5) already described. This battery potential is disconnected again after relay Sp60 has operated over contact $519p6$.

15 The difference between the present arrangement and the call finder AS4 in Fig. 4 resides in that the call finder AS6 sets itself on the calling line immediately after the reception of the call initiating impulse and consequently guards this 20 line and moreover brings about a corresponding setting of the associated final selector which in the case of Fig. 4 only takes place in response to an operation on the part of the operator. Thus there is now no possibility of the link being seized 25 by the operator for an incoming call or being taken into use by a fully automatic subscriber for the purpose of setting up a call.

The operator in the main exchange now makes her enquiry and sets up the connection in the 30 manner described above. A separate preparatory operation of the ringing key is not necessary. These switching operations serve to operate relay C40 (Fig. 4) in the known way, this remaining energized so long as the connecting link 35 is not used. For this purpose in Fig. 7 a thermo-relay Th1 is provided which is connected up over contact $526c40$ of relay C40. The contact $525th1$ of the thermo-relay then breaks the starting circuit for the call finder AS6. This connection 40 has the following significance: When on the release of the call the connecting link is released, whether by the removal of the plug by the operator or after the release of the speaking connection, contact $525th1$ remains open for an interval (for example one minute) so that in the 45 event of a newly registered call being present this cannot operate immediately over contact $516a6$. The starting of the call finder AS6 and thus the setting and guarding is delayed for a 50 period. During this time the operator or a fully automatic subscriber has the facility for setting up an incoming call in a manner which will not be described. Since the setting switch EW4 (Fig. 4) is stepped off normal on such a call the calling 55 impulse cannot at first become operative after the cooling down of the thermo-relay Th1 and the closing of contact $525th1$ since then the wiper EW1 (Fig. 7) has left its rest position. Accordingly the release of a connecting device which 60 has been taken into use is delayed for a period by the thermo-relay so that it cannot be taken into use immediately by a subscriber who has a call registered but instead although there are calls which have been registered the connecting 65 device remains for a short period at the disposal of, for example, fully automatic subscribers or the exchange operator for the purpose of setting up incoming calls. The arrangement shown in Fig. 7 can be applied in any subsidiary exchange 70 in which a thermo-relay dependent upon the corresponding C-relay and a thermo contact at a corresponding point in the starting circuit is provided. In each subsidiary exchange the release of the connecting device after a call is then delayed for a certain period so that during this 75

time even if registered calls are present in the system the exchange operator or a fully automatic subscriber can dial into the system. Instead of influencing the thermo-relay over the contact of a C-relay a working contact of the 5 call finder test relay (P6, $531p6$) can be provided in its place. The thermo-relay is then only heated up when a connection desired by one of the subscribers of a subsidiary exchange has been set up by the operator but the thermo-relay 10 is not influenced when an incoming connection is established by the operator or a fully automatic subscriber, in which case the call finder is not set. After such a call the semi-automatic subscribers have immediate access to the connecting paths. 15

What is claimed is:

1. In a telephone system wherein the extension of calls from subscribers' stations in a remote exchange is controlled by an operator in a 20 main exchange over an inter-exchange trunk line, means controlled by a subscriber in the remote exchange for placing a calling condition upon said trunk line to notify the operator of his desire to extend a call, means normally operated by the operator in response to the calling condition on said trunk line to extend a connection over said trunk line to the calling subscriber's line, and means operated at times before said operation of said last means by the operator to extend one or more other calls over said 25 trunk line irrespective of the calling condition thereupon.

2. In a telephone system wherein two exchanges are joined by a trunk line over which calls may be extended in either direction, and wherein the extension of local calls in one of the exchanges is controlled over said trunk line by an operator in the other exchange, means 30 operable by a subscriber in said one exchange to place a calling condition upon the trunk line thereby to notify the operator of his desire to extend a call, means normally operated by the operator in response to the calling condition on said trunk line to seize said trunk line and make 35 same busy, and means for extending other calls over said trunk line after the calling condition has been placed thereupon but before said trunk line has been made busy by the operation of said 40 last means. 50

3. In a telephone system, a two-way trunk line, means rendered effective by the extension of a call over said trunk line in one direction to prevent another call from being extended over the trunk line in the same direction within a predetermined interval of time after the termination of said first call, and means for extending a call over said trunk line in the other direction during 55 said interval of time.

4. In a telephone system, a two-way trunk 60 line, means for storing calls if the trunk line is engaged, whereby calls in one direction over said trunk line are held in waiting until the trunk line becomes free, and means for placing said trunk line exclusively at the disposal of calls in 65 the opposite direction for a predetermined interval of time after the trunk line becomes free thereby to prevent said waiting calls from monopolizing the use of said trunk line.

5. A telephone system as claimed in claim 4, 70 wherein said last means is effective only when the call in which said trunk line is engaged is a call in said one direction.

6. In a telephone system wherein the extension of local calls between subscribers in a remote ex- 75

- change is controlled by an operator in a main exchange over an inter-exchange trunk which is released after a local call has been extended, and wherein inter-exchange calls to or from subscribers in said remote exchange are also extended over said trunk line which is released upon the completion of said inter-exchange calls, means for placing said trunk line exclusively at the disposal of calls incoming to subscribers in the remote exchange for a predetermined interval of time after each release of the trunk line.
7. In a telephone system wherein the extension of local calls between subscribers in a remote exchange is controlled by an operator in a main exchange over an inter-exchange trunk which is released after a local call has been extended, and wherein inter-exchange calls to or from subscribers in said remote exchange are also extended over said trunk line which is released upon the completion of said inter-exchange calls, means for placing said trunk line exclusively at the disposal of calls incoming to subscribers in the remote exchange for a predetermined interval of time after each release of the trunk line following the use of the same in calls originated in said remote exchange, said last means being ineffective when said trunk line is used in an incoming call.
8. In a telephone system, a plurality of exchanges connected in series by trunk lines, the exchange terminating said series comprising a main exchange at which the extension of calls involving subscribers at the other exchanges is controlled, an operator's position at the main exchange, means responsive to the origination of a call at one of the exchanges for registering said call at said operator's position, said last means including means for registering said call at the originating exchange and at each exchange intervening between the originating exchange and the main exchange, said registration being thereby advanced to the main exchange over a route including a plurality of said trunk lines in series, and means for causing said registration of the call to recede from said main exchange to one of said intervening exchanges or to said originating exchange thereby to permit any desired portion of the route over which said registration was advanced to the main exchange to be used for another purpose.
9. A telephone system as claimed in claim 8, wherein, responsive to the release of the trunk lines in said portion of said route after the use thereof for said other purpose, said registration is again automatically advanced to said operator's position.
10. In a telephone system wherein the extension of calls between subscribers' lines is controlled by a remote operator over a trunk line common to said lines, means responsive to one of said lines initiating a call for placing a calling condition on said common trunk line to signal the operator of the initiation of a call, said common trunk line remaining idle in response to the operation of said means to enable the operator to extend a different call over said trunk line to a called one of said lines.
11. In a telephone system, a plurality of exchanges connected in series by trunk lines, the exchange terminating said series comprising a main exchange at which the extension of all calls between subscribers' lines is controlled, an operator's position at the main exchange, means responsive to the initiation of a call at one of the exchanges for registering said call at said operator's position, said registering means including means for placing a calling condition on the trunk lines intervening between the originating and main exchanges, said registering means being ineffective to make said trunk lines busy whereby said trunk lines may be used for extending calls to called subscribers' lines.
12. In a telephone system, a local exchange, subscribers' lines terminating in said exchange, a finder and connector switch link in said exchange for completing connections to and from said subscribers' lines, a control trunk extending from said local exchange to a remote operator, means for signalling the operator over said control trunk in response to a local subscriber initiating a call, said finder and connector switches in said link remaining idle and in unoperated positions during such signalling operation, means responsive only to said operator answering said call for operating said finder switch to find the calling line, and means controlled at times before the operator answers said call for operating said connector switch to extend another call to one of said local subscribers' lines.
13. In a telephone system wherein an operator at a main exchange remote from a local exchange controls automatic switches in the local exchange over a common control trunk to complete connections between local subscribers' lines, means responsive to the initiation of a call by a local subscriber for automatically signalling the operator over said control trunk, said means being effective only in case said control trunk is idle and also effective to maintain said control trunk available to the operator for completing other calls.
14. In a telephone system, a local exchange, a finder and a connector switch link in said exchange, subscribers' lines terminating in the banks of said finder and connector switches of said link, a control trunk extending from said link to a remote operator, a relay individual to each subscriber's line, means responsive to one of said lines initiating a call for energizing and locking the corresponding individual relay in energized position to register a call, means common to said lines operated in response to the operation of said relay for signalling the remote operator over said control trunk, said finder switch of said link unoperated in response to the operation of said last means and said link remaining idle to enable the operator to use the connector switch of said link to complete other calls.
15. In a telephone system wherein the extension of calls from subscribers' lines in a local exchange is controlled by an operator at a distant exchange over a trunk line common to said subscribers' lines, means responsive to one of said subscribers initiating a call for registering said call and signalling the operator over said trunk line, means for extending another call over said trunk line after said signalling of the operator but before the operator responds thereto, said first means maintaining said first call registered during the extension of said other call.
16. In a telephone system wherein the extension of calls from subscribers' lines in a local exchange is controlled by an operator at a distant exchange over a trunk line common to said subscribers' lines, means responsive to one of said subscribers initiating a call for registering said call in the local exchange, means controlled by said last means over said trunk line for registering said call in the distant exchange, means for thereafter extending another call over said trunk line.

line, means controlled by said last means for cancelling the registration of said first call in the distant exchange during said other call, said first means maintaining said first call registered in said local exchange throughout said other call.

17. In a telephone system wherein the extension of calls from subscribers' lines in a local exchange is controlled by an operator at a distant exchange over a trunk line common to said subscribers' lines, means responsive to one of said subscribers initiating a call for registering said call in the local exchange, means controlled by said last means over said trunk line for registering said call in the distant exchange, means for 10 thereafter extending another call over said trunk line, means thereupon controlled by said last means for cancelling the registration of said first call in the distant exchange, said first means maintaining said first call registered during the 20 time said trunk line is engaged in said other call and effective responsive to same becoming idle upon termination of said other call to control said second means to again register said first call in said distant exchange.

18. In a telephone system, an automatic exchange, a semi-automatic exchange, subscribers' lines terminating in each of said exchanges, a remote operator's position for controlling the extension of all calls initiated by subscribers in the 30 semi-automatic exchange, trunk lines extending from said semi-automatic exchange to said position, switching means in said automatic exchange having access to said trunk lines for the extension of calls from subscribers' lines in said automatic exchange to subscribers' lines in said semi-automatic exchange, means for controlling said switching means over a calling one of the subscribers' lines in said automatic exchange to test for and select an idle one of said trunk lines, means in said semi-automatic exchange thereafter controlled over said one trunk line to extend a connection from said one trunk line to a wanted subscriber's line, means responsive to the initiation of a call by a subscriber in the semi-automatic exchange for signalling the operator's position over an idle one of said trunk lines, said means causing said last trunk line to test idle to the switching means in said automatic exchange during such signalling to enable that trunk line to be selected for a call from said automatic exchange to said semi-automatic exchange.

19. In a telephone system as claimed in claim 18, means responsive to the operator answering said signalling for causing the trunk line to test busy to the switching means in said automatic exchange thereby to prevent that trunk from being selected for a call from said automatic exchange to said semi-automatic exchange.

20. In a telephone system, a group of subscribers' lines, a group of trunk lines accessible to said subscribers' lines for the extension of calls therefrom, switching apparatus common to

said subscribers' lines and controlled over a calling one thereof at times to search for and seize an idle one of said trunk lines, a second group of subscribers' lines having access to said trunk lines, an operator's position for controlling the extension of all calls from subscribers' lines of said second group, means responsive to the initiation of a call by a subscriber of said second group for placing a calling condition on an idle one of said trunk lines to notify the operator of the 10 subscriber's desire to extend a call, said last means effective to maintain said one trunk line idle irrespective of the calling condition thereon to permit the seizure of said one trunk line by said switching apparatus for a call from one of 15 the subscribers' lines of said first group.

21. In a telephone system, a group of trunk lines, a switch having access thereto, means for at times operating said switch to search for and seize an idle one of said trunk lines, a group of 20 subscribers' lines also having access to said trunk lines, an operator's position for controlling the extension of all calls from said subscribers' lines, means responsive to the initiation of a call by one of said subscribers for placing a calling condition on an idle one of said trunk lines to notify the operator of the subscriber's desire to extend a call, said last means maintaining said one trunk line idle to permit its seizure by said switch despite the calling condition thereupon.

22. In a telephone system, a two-way trunk line, means for extending a connection over said trunk line, means effective upon the release of said connection to prevent another connection from being extended over said trunk line in a 35 particular direction for a predetermined interval of time after the release of said first connection, and means for extending a connection over said trunk line in the opposite direction during said interval.

23. In a telephone system, a plurality of groups of lines, a line accessible in common to said last lines, means for extending a connection over said common line from any of the lines in one of said groups, means controlled by the release of 45 said connection for preventing the extension of another connection over said common line from any line in said one group for a predetermined period of time, and means for extending a connection over said common line from any line of 50 another of said groups during said period.

24. In a telephone system, a plurality of groups of subscribers' lines, a trunk line common to said subscribers' lines, means for extending a connection from one of said subscribers' lines 55 over said trunk line, and means controlled by the release of said connection for preventing the extension of another connection over said trunk line from any of the subscribers' lines in the same group as said one line for a predetermined period 60 of time.

EDUARD WOCHINGER.
